CLAIM

The ornamental design for an electronic candle as shown and described.

DESCRIPTION

FIG. 1 is a front elevational view of an electronic candle showing my new design;

FIG. 2 is a left side view thereof; and,

FIG. 3 is a perspective view thereof.

The rear elevational view is the same as the front elevational view. The right side view is the same as the left side view.

1 Claim, 3 Drawing Sheets**FIG.1**

FIG.2
